(57) **CLAIM**

The ornamental design for a switch housing with a permanent magnet cradle, as shown and described.

DESCRIPTION

FIG. 1 is a top perspective view of a switch housing with a permanent magnet cradle for a self-powered switch showing our design;

FIG. 2 is a side view thereof;

FIG. 3 is an opposing side view thereof;

FIG. 4 is an end view thereof;

FIG. 5 is an opposing end view thereof;

FIG. 6 is a top view thereof; and,

FIG. 7 is a bottom view thereof.

The broken lines in the drawings depict portions that form no part of the claimed design. The dot-dash broken lines describe bounds of the claim forming no part of the claim.

1 Claim, 7 Drawing Sheets
